US00D748591S

(12) **United States Design Patent**
Krishnan et al.

(10) **Patent No.:** US D748,591 S
(45) **Date of Patent:** ** Feb. 2, 2016

(54) **KEYED SPINDLE**

(71) Applicant: **Veeco Instruments Inc.**, Plainview, NY (US)

(72) Inventors: **Sandeep Krishnan**, Princeton, NJ (US); **Keng Moy**, Basking Ridge, NJ (US); **Alexander I. Gurary**, Bridgewater, NJ (US); **Matthew King**, Montville, NJ (US); **Vadim Boguslavskiy**, Princeton, NJ (US); **Steven Krommenhoek**, Annandale, NJ (US)

(73) Assignee: **Veeco Instruments Inc.**, Plainview, NY (US)

(**) Term: **14 Years**

(21) Appl. No.: **29/514,586**

(22) Filed: **Jan. 14, 2015**

Related U.S. Application Data

(62) Division of application No. 29/416,216, filed on Mar. 20, 2012, now Pat. No. Des. 726,133.

(57) **CLAIM**

The ornamental design for a keyed spindle, as shown and described.

DESCRIPTION

FIG. 1 is a top perspective view of a keyed spindle showing our new design;

FIG. 2 is a right side view thereof, the left side view being a mirror image of the right side view;

FIG. 3 is a front view thereof;

FIG. 4 is a rear view thereof;

FIG. 5 is a top plan view thereof; and,

FIG. 6 is a bottom plan view thereof.

The broken line in the figure drawings represents unclaimed environment only and forms no part of the claimed design.

1 Claim, 3 Drawing Sheets
